UNITED STATES PATENT OFFICE.

MORRIS GOLOMB, OF NEW YORK, N. Y.

STRIKING-BAG PLATFORM.

Application filed November 11, 1924. Serial No. 749,274.

To all whom it may concern:

Be it known that MORRIS GOLOMB, a citizen of the United States, residing at New York city, in the county of New York and 55
5 State of New York, has invented certain new and useful Improvements in Striking-Bag Platforms, of which the following is a specification.

This invention relates to an improvement 10 in platforms for striking bags, wherein the bag, usually an air-filled bladder protected by an outer covering, is suspended from the platform and driven against the same by the blows of the user, to train the eye and judgment and striking muscles.

Platforms of this type are usually flat and solid, and, when flat, open to the objection that the line of force of the bag, when driven against the platform, is necessarily 20 against a surface at an angle other than a right angle to such force, as the bag is swinging in the arc of a circle. This dissipates some of the force of the bag, and the rebound is necessarily of materially less 25 force than the impact, hence the bag movement is comparatively slow.

In the improved construction, however, the platform is dish or saucer shaped, that is, concaved, with the margin which ordinarily 30 receives the bag impact substantially at right angles to the line of force of the swinging bag. Hence the rebound force is more nearly that of the driving force, and the bag is "fast," which is to be highly desired.

Furthermore, the improved platform is cut out to leave open spaces to admit proper light directly to the bag, during movement, and thus permitting training in this particular under normal light conditions.

The invention is illustrated in the accompanying drawings, in which:—

Fig. 1 is a perspective view of the improved platform, showing a bag connected therewith, and the platform supported from a fixture.

Fig. 2 is a transverse sectional view through the platform, the bag being shown in broken elevation.

60 The improved platform comprises a circular disk-like member 1, of metal, wood,

or other appropriate material, having a partly rolled marginal edge 2, from which the lower surface of the platform is concaved, as clearly apparent in Fig. 2.

The platform proper, as completed, is of skeleton form, that is involves a marginal edge or flange 3, a center section 4, and bars 5, radiating from the center section, and thereby providing openings 6, through 60 which light may freely pass from above.

The center section 4, is provided with a swivel or universal support 7 for the usual striking bag 8, and this bag is hung so as to contact with the marginal flange 3 when 65 swinging. As such marginal flange is rounded downwardly and outwardly from the center section 4, incident to the concaved formation of the platform, it follows that the line of driving force of the bag 70 when swinging is directed against a surface substantially at right angles to such line of force, hence the rebound force is materially greater than would be the case if the platform was flat.

75 Thus the bag is very much "faster" with the improved platform than with the usual platform, a result highly desired in training devices of this type.

The platform is to be supported in any 80 desired manner, as for example, through studs 9 rising from the upper sides, and removably engaging arms or braces 10, two of which in the instance shown extend in substantially parallel relation to a bracket 85 plate 11, adapted to be secured to a suitable fixture, the third brace 10 being inclined and connected to an independent bracket plate 12.

The openings in the platform are in sufficient area to freely admit the necessary light from above the platform to avoid shadows on the bag, and render the same 90 equally lighted on all sides.

I claim:

1. A striking bag platform, comprising a structurally integral casting having a substantially flat central portion, and an edge curving downwardly and outwardly therefrom with a rounded margin.

100 2. A striking bag platform comprising a structurally integral casting having a sub-

stantially flat central portion, and an edge curving downwardly and outwardly therefrom with a rounded margin, the flat portion being formed with a series of openings.

5. A striking bag platform comprising a structurally integral casting having a substantially flat central portion, an edge curv-

ing downwardly and outwardly therefrom with a rounded margin, the flat portion being formed with a series of openings, and ¹⁰ means at the center of the flat portion for supporting the striking bag.

In testimony whereof I affix my signature.

MORRIS GOLOMB.
